UNITED STATES PATENT OFFICE.

JOHN W. WILLIAMS, OF NEW YORK, N. Y.

MECHANISM FOR REGULATING CLOCK-PENDULUMS.

SPECIFICATION forming part of Letters Patent No. 256,938, dated April 25, 1882.

Application filed February 4, 1882. (No model.)

To all whom it may concern:

Be it known that I, JOHN W. WILLIAMS, of the city, county, and State of New York, have invented certain new and useful Improvements 5 in Mechanisms for Regulating Clock-Pendulums, of which the following is a specification.

This invention has reference to an improved mechanism for regulating the pendulums of clocks from the central arbor of the same; and 10 the invention consists of a pinion placed upon the central arbor back of the dial and provided with an arm which passes along the socket of the hour-hand to the front part of the dial, the pinion meshing with a guided 15 rack-piece which carries the movable stud of the pendulum-rod, so as to adjust the same toward or away from the upper fixed stud of the same.

In the accompanying drawings, Figure 1 represents 20 a front view with my improved pendulum-regulating mechanism. Fig. 2 is a detail front view of the regulating mechanism with the dial removed, and Fig. 3 is a vertical transverse section of the same on line $\alpha\alpha$, Fig. 2.

Similar letters of reference indicate corresponding parts.

A in the drawings represents the central arbor of a common clock-movement, the latter being provided with an escapement-wheel and 30 anchor at the upper part of the dial, in the nature of French clocks.

Upon the central arbor, A, back of the dial, is placed a loosely-turning pinion or toothed segment, B, which is retained in position on 35 the front part of the movement and provided with a fixed arm, d , which extends along the socket of the hour-hand to a point above the dial-plate, where it is bent outwardly, so as to form a kind of handle or pointer, whereby the 40 pinion may be turned around the arbor. The pinion B meshes with a rack-piece, C, which is guided by longitudinal slots e on fixed studs e' of the front plate of the clock-movement,

the rack-piece carrying at the lower part a slotted stud, f , which moves vertically toward 45 or away from the fixed upper stud, f' , of the pendulum-rod D. The movable stud f is split so as to engage the flattened upper end of the pendulum-rod.

By means of the fixed arm d of the pinion 50 B the movable stud f of the pendulum-rod may be adjusted toward or away from the fixed stud f' of the upper end of the pendulum-rod, and thereby the length of stroke of the pendulum increased or decreased without adjusting the ball on the pendulum-rod, as now customary in this class of clocks. A small graduated scale may be arranged on the dial below the end of the pointer d , so as to facilitate the adjustment of the pendulum to any 55 desired degree required. By this means an easily-operated and simple attachment for common clock-movements is provided, which permits the adjustment of the pendulum so as to regulate the length of the stroke to a nicety 60 in a more convenient manner than by adjusting the ball, and at less expense than by the bevel-gear and screw adjustment of French 65 clocks.

Having thus described my invention, I claim as new and desire to secure by Letters Patent—

As an improvement in clocks, the combination, with the center arbor, of an axially-turning pinion or toothed segment having a fixed pointer-arm bent over the dial, with a vertically sliding and guided rack carrying a split movable stud, and with a pendulum-rod suspended from a fixed stud above the movable stud; substantially as set forth.

In testimony that I claim the foregoing as 80 my invention I have signed my name in presence of two subscribing witnesses.

JOHN W. WILLIAMS.

Witnesses:

PAUL GOEPPEL,
CARL KARP.
